Primary Examiner — Cynthia R Underwood(74) *Attorney, Agent, or Firm* — Perkins Coie LLP**CLAIM**

The ornamental design for a spreading material container holding device, as shown and described.

DESCRIPTION

FIG. 1 is a perspective view of a spreadable material container holding device;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.
